MEANS FOR DRIVING SPINDLES IN TEXTILE SPINNING MACHINES

Filed Dec. 14, 1927

UNITED STATES PATENT OFFICE

JOSEPH BERLINERBLAU, OF WARSAW, POLAND

MEANS FOR DRIVING SPINDLES IN TEXTILE-SPINNING MACHINES

Application filed December 14, 1927, Serial No. 240,049, and in Great Britain December 15, 1926.

This invention relates to means for driving spindles in textile spinning machines, the said means being of the kind known as electric independent drives, wherein each spindle of the machine is rotated by its own electric motor, the shaft of which is coupled to or made to form a part of the spindle.

In known arrangements of this kind it has been necessary to support the motors or 10 motor casings on the frame of the machine, for example on the top and bottom rails; and particularly where existing machines have been converted to electric spindle drive the alterations necessary to provide this support have had to be made with precision in 15 order to preserve the correct alignment of the spindles or the alignment of the motor casings with the existing spindle bearings. Furthermore in applying the motor casings 20 to the spindles in such arrangements these casings have covered a considerable part of the length of the spindles, leaving insufficient clearance for the braking of the spindles manually as is still the practice in some places.

25 The object of this invention is to provide an electric drive for each individual spindle in such manner that it can be applied without in any way departing from the prevailing methods of mounting the spindles on 30 the machine, or in cases of conversion, without interfering with the mounting of the spindles in the machine to provide the requisite support for the motor casings.

To attain this object, according to the invention 35 the motor casings are supported by the spindles themselves, which latter form continuations of or are coupled to the motor shafts, in alignment therewith, means being provided to check the tendency of the casings 40 to rotate with the spindles under the influence of the magnetic flux and the friction in the bearings.

The invention and the advantages thereof 45 will be more readily understood by reference to the accompanying drawing in which an example of the improved drive is illustrated, one spindle only with its motor being shown for the sake of simplicity.

The figure is a vertical elevation partly in 50 section.

The spinning machine frame indicated generally at A includes a top rail *a* and a bottom rail *b* carried by stretchers *c*. The spindle *d* with its flyer *e* is supported in the top rail by means of a bush or sleeve *f* and in 55 the bottom rail by means of a socket *g* in which the lower end of the spindle fits. The socket *g* may be adjustable vertically to permit correct setting and horizontal alignment of the several spindles; this could for instance be 60 done by making the socket a sliding fit in the bottom rail as shown and locking it in the desired position by means of a set screw *h*. In view of the weight which the socket *g* has to support it is preferably provided with 65 a steel ball *i* against which the lower end of the spindle bears to reduce friction and consequent excessive wear.

To compensate for wear in the bearing in 70 the top rail *a*, the spindle where it passes through the bush *f* is preferably tapered as shown at *j* and the bush is likewise tapered so that when occasion arises the bush may be lowered to take up the slack and prevent the 75 spindle wobbling, this bush being locked in its adjusted position by means of the set screw *h*.

The motor for driving the spindle is indicated generally at B being preferably a three phase or other polyphase motor with a short circuited winding and working with any desired 80 low tension of variable frequency. As illustrated the motor is situated intermediate of the ends of the spindle which is preferably formed as a continuation of the motor shaft *t* although it may be joined to the latter. The rotor *t* which in the construction illustrated is composed of iron laminations is secured to the spindle in such manner as to rotate with it and is surrounded as usual by the winding arranged in the casing. The casing instead of being supported by the spinning frame directly as hitherto is supported by the spindle itself, and for this purpose it comprises a body portion *n* and upper and lower end-plates *o* and *p* secured to the said body portion by screws or other suitable means. The upper end-plate *o* is provided with a recess *g* forming a housing for an axial thrust ball or roller bearing *r*. The lower race 95 of this bearing rests on a shoulder on the 100

spindle said shoulder being for example formed by enlarging the diameter of the spindle, and the bearing is held in place in the recess by means of a cap u screwed into the said recess g .

5 The lower end-plate p is similarly provided with a ball or roller bearing v accommodated in a recess w in the end plate, but in this case the bearing need only be lateral thrust bearing as it does not have to sustain any weight but has merely to take up the radial pressure of the spindle. For convenience it is preferable to continue the increased diameter of the spindle so as to form a shoulder against which the lower bearing is positioned.

10 As the casing and winding have a tendency to rotate under the influence of the magnetic flux and the friction in the bearings when the spindle is rapidly revolving, means must be provided to prevent such rotation occurring.

15 The means illustrated by way of example consists of a tension spring x suitably secured at one end to the top cover or end plate o as for instance with the aid of one of the holding

20 down screws w' and anchored at the other end to the spinning frame, as for instance to the stretcher c . The spring in no sense aids in supporting the casing and as the tendency of the casing to rotate is not great the spring

25 need be only strong enough for this purpose.

30 The invention is applicable to all kinds of spinning machines, whether the spindles thereof operate flyers or rings, and in fact to any spinning motion wherein the motors and 35 spindles can be arranged as independent units, the invention being especially applicable to heavy duty machines for spinning hemp, flax and other fibres of a hard or coarse nature.

35 Having now particularly described and ascertained the nature of my said invention and in what manner the same is to be performed, I claim:

40 1. In a spinning machine, a frame, a spindle in the frame, an electric motor including a rotor and a casing, the rotor being mounted on the spindle, a shoulder on the spindle supporting the casing, and a resilient connection between the frame and the casing preventing turning of the latter.

45 2. An arrangement as claimed in claim 1 characterized by the provision of a thrust bearing interposed between the shoulder and the casing.

50 3. An arrangement as claimed in claim 1 characterized by the provision of an axial bearing interposed between the spindle and casing at the end of the latter opposite that mounted on the shoulder.

55 4. An arrangement as claimed in claim 1 characterized by the provision of a step bearing interposed between the lower end of the spindle and the frame.

60 In testimony whereof I have affixed my signature.

65 DR. JOSEPH BERLINERBLAU.
